Fig. 1

Fig. 7

Fig. 8

FIG. 1 is a front perspective view of a combined envelope and sheet for advertisement showing my new design in folded position, the back being plain;

FIG. 2 is a plan view thereof in an unfolded position;

FIG. 3 is a plan view thereof with the panel at the right folded inward;

FIG. 4 is a plan view with the panel at the left folded inward and the panel at the right folded thereon;

FIG. 5 is a plan view of a second embodiment of the design of FIG. 1, in a position as described for FIG. 4;

FIG. 6 is a plan view of an embodiment of the design of FIG. 1 in a position as described for FIG. 4;

FIG. 7 is a plan view of a fourth embodiment of the design of FIG. 1 in a position as described for FIG. 4;

The dash lines on the drawing represent perforations.

I claim:

The ornamental design for a combined envelope and sheet for advertisement, as shown and described.
